(57) **CLAIM**

The ornamental design for a display stand, as shown and described.

DESCRIPTION

FIG. 1 is a top perspective view of a display stand, showing my new design;

FIG. 2 is an enlarged top perspective view thereof;

FIG. 3 is a front elevational view thereof;

FIG. 4 is a rear elevational view thereof;

FIG. 5 is a left-side elevational view thereof;

FIG. 6 is a cross-sectional view thereof, taken along line 6-6 of FIG. 7;

FIG. 7 is a top plan view thereof;

FIG. 8 is a bottom plan view thereof; and,

FIG. 9 is a bottom perspective view thereof.

The broken lines showing a figurine and a soda can in FIG. 1 depict environmental matter and form no part of the claimed design. The remaining broken lines in the figures depict portions of the display stand that form no part of the claimed design.

1 Claim, 7 Drawing Sheets
